CIRCUIT BREAKER CASE

Charles Mune, Trenton, N.J., assignor to Heineyman
Electric Company, Trenton, N.J.

Filed Aug. 2, 1971, Ser. No. 168,534

Term of patent 14 years

Int. Cl. D13—03

U.S. Cl. D26—13

FIG. 1

FIG. 5

FIG. 3

FIG. 2

Fig. 6.

Fig. 4

FIG. 1 is a front elevational view of a circuit breaker showing my new design;

FIG. 2 is a side elevational view from the right of FIG. 1;

FIG. 3 is a rear perspective from the left of FIG. 1;

FIG. 4 is a bottom plan view;

FIG. 5 is a top plan view; and

FIG. 6 is a front, side and bottom perspective view of a two pole circuit breaker unit formed by placing in side-by-side relation two single-pole circuit breakers.

The broken lines are for illustrative purposes only.

I claim:

The ornamental design for a circuit breaker case, as shown and described.
